DESIGN FOR A FLOWER CANDLEHOLDER

Frank L. Shaffer, Los Angeles, Calif.

Application March 28, 1944, Serial No. 113,057

Term of patent 14 years

(Cl. D48—2)

To all whom it may concern:

Be it known that I, Frank L. Shaffer, a citizen of the United States, residing at Los Angeles, in the county of Los Angeles and State of California, have invented a new, original, and ornamental Design for Flower Candleholders, of which the following is a specification, reference being had to the accompanying drawing, forming part thereof.

Fig. 1 is a perspective view of a flower candleholder showing my new design; and
Fig. 2 is a side elevational view thereof.

I claim:
The ornamental design for a flower candleholder, substantially as shown.

FRANK L. SHAFFER.
